his ATTORNEY.

UNITED STATES PATENT OFFICE.

GEORGE BRANDER, OF SUTHERLAND, IOWA.

WASHING-MACHINE.

SPECIFICATION forming part of Letters Patent No. 527,264, dated October 9, 1894.

Application filed December 15, 1893. Serial No. 493,794. (No model.)

To all whom it may concern:

Be it known that I, GEORGE BRANDER, a citizen of the United States, residing at Sutherland, in the county of O'Brien and State of Iowa, have invented certain new and useful Improvements in Washing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improvement in washing-machines and has for its object to combine with a tub having independently adjustable rollers, a convenient form of stove for applying heat to the tub.

20 A second object of the invention is provide the receptacle, containing the clothes, with an inner perforated false bottom, on which the clothes rest in the process of washing. The false bottom, referred to, is suitably perforated to permit the dirt and sediment, pressed from the clothes during the operation of washing, to escape, or settle to the bottom of the tub.

25 I employ as the washing device two conical, fluted rollers, pivoted radially in said tub in position to rotate upon their own axes, and by rotating the tub, by means of the mechanism hereinafter described or its equivalent, bring all of the clothes contained in the tub successively under both of said rollers.

30 I attain the above purposes by the mechanism illustrated in the accompanying drawings, in which—

Figure 1 is a perspective of my invention, 40 with a portion of one side of the tub removed. Fig. 2 is a vertical section of the device as illustrated in Fig. 1.

Similar letters and figures refer to similar parts in each view.

45 The general frame of the machine consists of suitably braced, vertical, parallel standards A—A. A cross-bar C, removably seated in vertical slots 1—1, formed in the upper ends of the standards A, forms the brace for the 50 upper portion of the frame, and serves to suspend two frames D—D. The latter frames are attached to the cross-bar C by means of

two vertical rods E—E, sleeved at their upper ends in said bar C, and provided at their upper ends with a suitable nut B, and attached in pairs at their lower ends to the frames D—D, respectively. The attachment of the rods E to the frames D is accomplished by passing the lower ends of said rods through the horizontal cross-plate F which forms the upper portions of the frames D, and rigidly fastening the said rods to said plate F. Between the plate F and bar C there is seated on each of the rods E coiled springs G, which permit the vertical oscillation of 65 said frames D, and by means of the nuts B, the pressure of springs G on frames D can be regulated as desired. A vertical shaft H is rigidly seated, at its upper end, centrally in said bar C, and extends downward, and 70 suitably stepped at its base in the center of the tub J. That portion of the shaft H below the bar C is formed of two parallel rods K—K, and two short eye or hook bolts L are seated a short distance apart in the inner 75 side of the frames D—D, with their eyes or hooks 2 encircling the rods K, and thereby adapted to permit of the vertical movement and lateral oscillation of the frames D, to permit the rollers M to adjust themselves to 80 the uneven surface of the clothes. The rollers M are of a conical, longitudinal, fluted formation, and are pivotally seated radially, with their smaller ends toward the center, in the bottom of the frames D, respectively. 85

The tub J is rigidly seated centrally on the upper end of a short vertical shaft N, the latter being pivotally journaled in the cross-plate O of the frame of the machine, and provided at its lower extremity, beneath plate 90 O, with a beveled gear P.

A rotating shaft R is journaled transversely in the frame A below the tub J, and provided with a suitable crank arm R', and provided near its center with a beveled pinion S, 95 adapted to engage and actuate the gear P, and thereby communicate rotation to the tub J.

T is a perforated false bottom in the tub J, suitably supported a slight distance above the bottom of said tub, and the clothes to be washed are placed in said tub upon the bottom T and between the latter and the rollers M. By providing the plate with a central

opening of the same diameter as the diameter of the lower end of the shaft, the plate will also act as a means for securing the lower end of the shaft, which may pass loosely therethrough and rest upon the bottom of the tub. The rotation of the tub J causes the rollers M to traverse the entire inner area of said tub, pressing the clothes meanwhile back and forth through the hot water in the latter.

10 By forming the shaft of the machine with vertical rods A and mounting the roller carrying frames thereupon, each independently of the other, the capacity of the machine is doubled and the rollers are each permitted 15 to rise or fall according to the particular amount of clothing under each, irrespective of the amount under the other.

V is the usual gasoline reservoir, communicating through pipe W to the usual burners X X, under the tub J; or any other suitable means for heating the water in the tub and boiling the clothes meanwhile may be employed.

20 The feed pipe W, at the locality of the shaft H, is slightly bent laterally to pass around said shaft.

The bar C is removably seated in the frame of the machine, so that it and the frames D may be together lifted from the tub for the 30 purpose of placing the clothes in the latter, or removing them therefrom.

If preferred, the rotating shaft R may be suitably connected to a wind-mill, or other actuating machinery.

35 In addition to the above named advantages, a further advantage in my invention is that

it may be used outside of the house in summer-time, and thereby dispense with the overheating of the building.

If preferred, the use of the gasoline attachment may be dispensed with, and the machine used by pouring hot water into the tub J.

All of the clothes are subjected to the pressure of each of the rollers M, and the dirt is removed by the continuous passage of the hot 45 water and steam through the clothes, the detached dirt dropping down through the perforations in the removable bottom T to and upon the normal bottom of the tub, from whence it can be readily removed by taking 50 out the bottom T.

What I claim as my invention, and desire to secure by Letters Patent of the United States, is—

In a washing machine, the combination, 55 with a frame, of a brace secured to the upper portion thereof, a rotatable tub upon the frame, a vertical shaft having its upper end rigidly secured to the brace and its lower end set in the bottom of the tub, and its central 60 portion formed of two parallel rods, two roller frames suspended from the brace, one upon each side of the vertical shaft, and movably secured to its respective rod, and means for operating the tub, substantially as set forth. 65

In testimony whereof I affix my signature in presence of two witnesses.

GEORGE BRÄNDER.
